SASH CORD FASTENER

Earl M. Trammell, Sr., and Earl M. Trammell, Jr.,
St. Louis, Mo.

Application October 11, 1948, Serial No. 53,922

11. Claims. (Cl. 16—202)

1

This invention relates to improvements in counterbalance connections for sliding sash, and more particularly to connectors and fixtures of a novel and improved type, for use in and on the sliding sash, counterbalance and sashway, in assemblies of a type permitting removal of the sash, the invention including certain combinations of fixtures with the sash and framing as making for novel results.

More recent improvements of sliding sash assemblies are directed to provisions enabling the sash to be readily removed from and reapplied into the frame structure forming the sashway. Such facilities make for added convenience incident to periodical cleansing of glass sash, the removal thereof for painting and similar purposes, and conducive to ease in thorough renovation, and with other advantages. Such developments however, inasmuch as it is highly desirable to counterbalance each sliding sash for ease in its opening and closing movements, have heretofore left unsolved the problem of arresting or keeping captive the counterbalance and flexible tension element connected thereto, when the sash is removed. This shortcoming of prevailing provisions for removal of the sliding sash, detracts largely from the advantages of provisions for sash removability. It is accordingly a major and principal objective of the present improvements, to provide automatically for the capture and retention in place of a counterbalance tension element, incident to the removal of the sash, and to arrest the said counterbalance parts in such position and relation that the effective connection of the sash to the counterbalance, is re-established upon reapplication of the sash to its sashway.

A further important objective of the invention in its most advanced form, consists in the attainment of the foregoing objective, in usage, by manipulation only of the sash element.

Yet another valuable object of the invention is attained in the provision of a practical separable connection between the sash and counterbalance, and which is particularly, but not exclusively, adapted for use with removable sliding sash units.

A further major objective of the invention is realized in the provision of a plurality of companion separable fixtures or connectors of such nature that a counterbalance cord for example, is either connected to the sash, as in normal sash operation, or may selectively be held captive in the sashway.

Yet another important object of the invention is attained in certain novel adjunctive hard-

2

ware items of advanced design, for use with removable sash elements and the coacting sashway structure, for the purposes stated.

More particularly stated in reference to certain of the aforesaid fixtures, there are realized provisions for the automatic arrest of a counterbalance or counterbalance cord, when a removable sliding sash is brought to a predetermined removable position, automatically such fixtures serving to reconnect the sash to the counterbalance when the sash is restored to operative position, following removal.

The foregoing and numerous other objects will more clearly appear from the following detailed description of a presently preferred embodiment of the invention, particularly when considered in connection with the accompanying drawing, in which:

Fig. 1 is an elevational view of a window assembly of a type embodying double hung sash of sliding type, and embodying the present improvements, Fig. 1 being on a somewhat reduced scale as compared to the remaining figures;

Fig. 2 is a vertical sectional elevation, partly broken away, and taken along line 2—2 of Fig. 1;

Fig. 3 is a fragmentary sectional view taken in a horizontal plane, and particularly located by line 3—3 of Fig. 1;

Fig. 4 is a fragmentary sectional view with parts broken away for clearness, illustrating certain of the elements of trackage, guide rollers coacting therewith, and certain of the fixtures on the sash and in the sashway, this view being particularly located by line 4—4 of Fig. 3;

Fig. 5 is a fragmentary sectional view in a horizontal plane, to show detail of one of the connectors, particularly as viewed along 5—5 of Fig. 4;

Fig. 6 is an elevation view, partly in section, of a pair of coacting connector parts for arresting counterbalance function and positioning the counterbalance cord incident to sash removal;

Fig. 7 is a view similar to Fig. 4 and showing a slightly modified form of the connectors or fixtures for the purposes stated, preferably utilized for arresting and keeping captive, the counterbalance of the upper sash element, Fig. 7 being taken along line 7—7 of Fig. 2, but with the upper sash in a lowered position, ready for removal;

Fig. 8 is a fragmentary sectional view, partly in elevation, of one of the counterbalance captive fixtures in the form shown by Fig. 7, together with certain of the connector elements, Fig. 8 being taken along line 8—8 of Fig. 7, and

Fig. 9 is an elevational view, isometric in nature,

showing a form of counterbalance of spring loaded type suitable for use in the present assembly.

Referring by characters of reference to the drawing for description of the parts and their functions, the upper sash is indicated generally at 10, and the lower sash generally designated at 11. Each such sash comprises sash stiles 12 and 13, check rails 14 and 15, the usual inside casing, stool 17, apron 18, and a blind stop 19, together with other usual framing and sash elements, all familiar to those skilled in this art. There may, however, be mentioned for completeness, a vertical or pulley stile indicated at 25, into a groove or channel of which is set the parting bead 28.

The sash assembly illustrated is of a type including provisions for guiding each of the upper and lower sash to assure smoothness and ease of operation, and is further of such nature as to facilitate removability of the sash, as heretofore mentioned. These latter provisions include, at the opposite sides of each sashway, a metal track element 30 provided with suitable fastening portions 31, by which each such rail is kept in place in vertical position within the sashway. The term "sashway" as employed herein, denotes the several channel-forming elements within and along which each sash 10 or 11 is guidedly movable and restrained to normal operation in its own plane. For example as to the upper sash, the sashway is formed by the members 28, 25 and 19, at each of the opposite vertical margins, together with the transverse or horizontal elements at the ends of the window frame.

Coacting with the rails 30, there are provided in the assembly shown, a plurality of roller fixtures, some of which are generally indicated at 34, and others, later described, at 55 and 55', and 85 and 85', which are of greater length and include certain connector elements, later described. Those roller fixtures generally designated 34, are at the opposite lower margins of each sash as shown, and need include only a short U-shape metal member the sides of which are bridged by a roller axis element such as pin 36 (Figs. 3, 4 and 7) about which rotates a roller 37 of metal, fiber or other material making for long life and quiet operation. Each roller 37 is provided with a V groove 40, and each of the rails 30 is provided with a beveled or apiced ball or roller-engaging surface portion, as will appear from Fig. 3 for example.

By preference a substantial clearance is provided, considerably more than usual in a sliding sash assembly, between the pulley stiles and each adjacent vertical sash stile, this abnormal spacing being provided along each of the opposite sides of each sash, as is indicated at 41.

For the purpose of permitting easy removability of the sash, each of the rails 30 on one side of the frame, in this case the right hand side, is provided in particular locations along the sashway, with recessed or cutaway portions preferably, but not strictly necessarily, of a generally C-shape, these being two such recesses, indicated at 43, for each of the rollers 37 on the right hand side (Fig. 4) of the lower sash. Such cutaway portions in the rail at the right hand margin of the upper sashway, are relatively inverted, and are indicated at 44, one of these being shown by Fig. 7. This particular conformity of the cutaway parts of the rail, is imparted so as to include a sloping rectilinear portion 45 in each recess to impart to the rollers under certain conditions a

lateral camming effect, the purpose of which will later more fully appear.

The clearance provided laterally of each of the sash, as indicated at 41, together with the provisions of the several cutaway portions 43 and 44, enables each of the sash when it is moved to bring its pulleys 37 opposite the companion cutaway portions, to be laterally shifted, i. e. in the plane of the sash and to the right (Figs. 4 and 7) the clearance further being such that when thus moved, the sash may be withdrawn by a forward movement of its opposite margin, which will now clear the adjacent stop elements. Once this is done, the sash may then be drawn further to the left in its own plane, thence outwardly and free of the several elements of the window structure.

The structure as thus far described includes certain features of a novel removable sash assembly disclosed and claimed in a copending application of these applicants, filed May 11, 1949 under Serial No. 92,572, and entitled Window Units and Accessories. The present application distinguishes from said copending application in being directed to the features and elements providing for automatic connection and disconnection of the counterbalance to the sash. It should here be noted that the term "removable," and related and derived terms, are not intended to impart any necessary restriction of present subject matter, as to its application and use, to sash and sash assemblies of the particular nature herein disclosed, the hardware, fixture and connector items to be described being susceptible of application to numerous other forms of sliding sash.

In the example shown by the drawings, it is contemplated that removability be provided for when each sash is moved to a more or less predetermined location in its own sashway. As a practical matter, this removal position is best provided for as each sash approaches its maximum open position, e. g., the upper sash 10 will, for purposes of removal, be brought to or near a bottom position, and the lower sash will be moved to or near its upper most position. This arrangement assures the normal guided actuation of the sash throughout all or most of its usual range of opening and closing movement.

With the foregoing noted for a general understanding of purpose of the several fixtures, connectors and other hardware items, it may be mentioned that each sash is provided above and generally in line with its sashway, with one or a pair of counterbalance units. Since these nuts per se form no part of the present improvements, a general reference thereto is sufficient by noting that, as shown by Fig. 9, the unit generally indicated at 50 contains a spring, usually one of clock-spring type (not shown), together with a spring arbor and spring anchorage within the casing, the spring being operatively connected to a tape indicated at 51 and provided with an attachment loop 52, the unit 50 being provided with attachment extensions 53 and 54 suitably apertured for mounting in the upper portion of the window frame. It has been found that, in a guided rolling sash such as disclosed, windows of usual or narrow width are sufficiently counterbalanced with a single unit 50, whereas in windows of greater width, a pair of counterbalances are usually provided, one above each side of each sashway. As to the connection from sash to counterbalance, a flexible metallic tape 51 is shown; according to manufacturing preference and availability it will be understood that such a flexible tension element may consist of a cord, chain, rope or other

equivalent, the term "cord" being herein employed, in a generic sense, and without any intended restriction to this particular type of tension element.

Proceeding first to describe generally the nature of the connectors or fixtures serving the general purposes of arresting and positioning the counterbalance cord 51, and assuming for brevity of description that each sash be equipped with dual counterbalance units, the description of one thereof will suffice for both, with certain minor differences in the hardware elements at opposite sides of the sash, as hereinafter noted.

As to the connectors or fixtures, reference is first directed to Fig. 7, particularly in the right hand side of which there is seen a first fixture generally indicated at 55 and which includes a mounting plate 56 suitably apertured to receive attachment screws 57. Extending outwardly of the base or mounting plate 56, is one or a pair of plate elements 58, a description of one of which will suffice. This latter is provided with an acute angled projecting arm 60 which may be struck out of the plate portion 58, and with a second such projection extending horizontally and indicated at 61.

A second fixture consists of a plate element generally designated at 65 (Figs. 7 and 8). This is provided with a right angular outstruck portion 66. The plate portion of fixture 65 is of a generally rectangular form, and is extended to provide an integral projection or tongue 67, the outer or free end margin of which is characterized by divergent sides, as will appear from Fig. 7, and just above this divergent portion is a recessed or shouldered region 68. Near its upper margin, the plate or body of this fixture is apertured as at 70 to receive the connecting loop 52 through which the fixture is connected to the cord, tape or the like, 51.

A third fixture of this assembly coacting principally with the second such fixture 65, is generally indicated at 71. This member is or may be formed entirely of a single element of resilient spring stock, such as spring steel. It is in the nature of a spring clip, and includes a normally vertical mounting base or tang 72 which is or may be secured as by rivets 73 to an adjacent rail 30, being thus fixed in position in the sashway. The base 72 of the third fixture is continued downwardly (Fig. 8) through an offset portion, into a vertical part 74, this latter being folded back upon itself to provide a pair of spaced guide plates, one consisting of the body part 74, spaced from and parallel to which is the opposite guide plate 75. These guide plates are each provided with a divergent upper end, so that the passageway between the plate member 74-75 is entered by a converging throat, as will later appear, by the tongue and plate of fixture 65.

Further in reference to the third fixture 71, this may as shown, extend below the portion 74-75 through a right angle bend, thence to form a vertical spring jaw 76, this jaw being bent back upon itself to form a companion resiliently related jaw 77 with an inturned and partly folded end 80. As will appear from Fig. 7 lower portion, the particular formation given, the free end of jaw 77 is such that the part 80 will, when the tongue 67 enters the space between the jaws, serve to interfit the shoulder formation 68. In this manner, the tongue 67 and the spring jaws 76 and 77, are firmly yet detachably interfitted, for temporary securement purposes. Inasmuch as the second fixture 65 is secured to the cord or

tape 51 and the latter to the counterbalance, it now becomes apparent that when fixtures 65 and 71, constituting the parts of a detachable connector, make the connection noted, the spring loading of the counterbalance 50 on the cord or tape is effectively resisted by the spring jaws and tongue, and thus the balance action is arrested to permit removal of the sash as will appear, and will be automatically restored upon reinsertion of the sash.

A further feature providing for a lateral interlock incident to connection of the fixtures 55 and 65, is shown by Fig. 7 as an outstruck point element 81, best seen in Fig. 7, which, with the parts 55 and 65 connected, extends through an aperture 82.

It will have been observed from Fig. 7 that, assuming a dual counterbalance connection to the upper sash 10, the assembly and coaction of connector elements at the left hand side (Fig. 7) is or may be identical to that described, the parts therein being indicated by prime but otherwise corresponding reference characters, the parts of the three fixtures being identical at opposite sides, except for formation in right and left handed relation.

It has been noted as a preference that the lower sash be brought fully in or near its maximum raised position, to permit removal thereof from the sashway, and for this reason a somewhat modified form of the companion fixtures forming the counterbalance arrestor, are utilized in connection with the lower sash. In this case (Fig. 4) a first or sash mounted fixture generally designated at 85 consists of a mounting plate apertured to receive and provided with mounting screws 86. Turned outwardly of and normal to the base plate is a plate 87, of a generally rectangular shape one or a pair of which may be used. Struck out of plate 87 is a projection 88, while part of the lower margin of plate 87 is bent downwardly at an acute angle similarly to the portion 60' (Fig. 6) as indicated at 90.

The second fixture for the lower sash 11 is affixed to the counterbalance through its cord or tape, and is generally indicated at 95 (Fig. 6). The element 95 preferably consists of a substantially rectangular plate element, the lower margin of which is acutely upturned and indicated at 96, the latter provided with an aperture in the region of the fold between 95 and 96, and indicated at 97, for the reception of a point portion 98 on fixture 85 (Fig. 4) releasably to hold the first and second fixtures against lateral displacement. The plate or body of this second fixture 95 includes an upwardly extended tapered tongue 100, and at one side of the tongue the plate is apertured as at 101 to receive the connecting loop 52 serving to attach this fixture to the tape or cord 51.

Coacting particularly with the tongue 100 is a tapered socket structure 102, the taper of which conforms at least substantially to that of the tongue 100. This third fixture or socket structure is fixedly positioned in the sashway or otherwise along the path of movement of the sash, with the larger end of the socket downwardly presented for the reception, when the sash is brought to this predetermined position, of the tapered tongue 100. Attachment of the socket structure or third fixture is conveniently provided for by an extension 103 which may be riveted for example as at 104 to the adjacent rail 30. As best appears from Fig. 5, it is preferred that the socket structure 102 be of a flat-

tended aspect to the interest of economy of material and space requirement. The socket fixture 102 may be formed of a single element of spring metal, with the portion 103 turned outwardly, thence across, then parallel to the out turned side, so that the tapered sides in effect serve as jaws to grip the tongue 100.

It will now have become evident that as the lower sash is brought substantially to its maximum open position, the fixture 95 following the sash movement, the tapered tongue 100 will enter the socket 102, and during such relation of parts, the counterbalance with tension on the cord or tape 51 will maintain the elements 95—100—102 in interfitted position, thus enabling the separation of the fixture 85 from fixture 95 incident to manipulation of the sash, and upon reinsertion of the sash after removal, reengagement of portions 90 and 96 with the lowering movement of the sash, again separates 100 from the socket 102 and enables a normal counterbalance sash actuation.

Assuming the upper sash 10 to be in operative position in the sashway and that it be desired to remove same, this sash is lowered to a position slightly above that which, but for present improvements, would be its lower limit. In this position, the rollers 37 will be positioned opposite the cutaway or recessed portions 44 in the adjacent rail, substantially as shown by the right hand side of Fig. 7, it having been noted as necessary to provide the recesses 43, 44 in the rails, on only one side of the sashway, for example in the right hand rails of each, as shown by Figs. 4 and 7. There being one such recess such as 44 for each of the paired rollers 37 on the right hand side of the assembly, the sash is first given a slight lifting movement of the order of one-eighth to one-fourth inch, this serving the purpose of lifting the pointed portions 81—81' each from the adjacent opening 82 or 82'. Following this initial slight lifting movement, the cutaways 44 will now permit a substantially lateral shifting movement of the sash, in this case to the right of Fig. 7. This movement has the effect of slidably disengaging the element 60 (Fig. 8) from overlying relation to the acutely upturned marginal portion of fixture 65, such portion being indicated at 59. In the case of the left hand side of the assembly, such movement of element 60 will take place away from the pulley stile 25 on the left hand side (Fig. 7). Incident to this shifting movement each of the pulleys 37 will enter the cutaways or recesses 44, and the left hand margin of the upper sash 10 will now clear the adjacent stop structure, and the margin of the sash now thus cleared, may be moved freely to the left and at the same time lifted, so that fixtures 55 and 65 and their prime numbered counterparts, will have become separated and the normal operative connection therebetween is broken.

Prior to the aforesaid shifting and lifting movements of the sash, it will have appeared from earlier description that the fixture 55 carrying tongue 67, will have been brought downwardly by the corresponding movement of the sash, and to the extent to bring the tongue 67 to a position between the spring jaws 76 and 77 of the third or spring fixture 71. The divergent nose portion of the tongue 67 first acts to spread the spring jaws, and as it further enters the space therebetween, the reentrant end portion 80 of jaw 77 will spring back (to the right in Fig. 7) into firm interfitting engagement with the shoulder 68 on the tongue. Since fixture 65 is secured

to the balance cord or tape 51, it will now have appeared that when the fixtures 65 and 71 are connected as described, the balance cord, hence the counterbalance unit 50 are retained in status quo, the balance thus temporarily being arrested in its function and the cord or tape held captive in a position to facilitate and assure its reconnection to the sash when desired. Such reconnection may take place as is intended, solely by manipulation of the sash.

Assuming now that it be desired to reinsert the upper sash 10, the sash is applied to the sashway with its right hand margin (Fig. 7) in a position about to enter the right hand edge of the sashway, and the left hand sash stile brought as close as possible to the parting bead. By a further lateral shifting movement the right hand margin is brought completely into the sashway following which the entire sash may easily be brought into its normal operative plane. The ensuing step is a slight lifting movement of the sash which causes each of its right hand pulleys 37 to engage, with a lateral camming effect to the left, the inclined surfaces 45 of the adjacent recesses 44. Continued lifting movement of the sash brings the outstruck portion 61 upwardly into abutting engagement with the projection 66 of fixture 65, with the result that the tongue 67 is drawn outwardly of its position between the spring jaws 76 and 77. Following such movement, fixture 65, under the tension of the counterbalance cord, is quickly raised to bring the hook-forming element 59 of this fixture into engagement with the companion acute abutment 60, at which time the sash and the counterweight are again connected for normal balanced sliding actuation.

The actuation of the lower sash and its several connectors although briefly above referred to, may be more completely described by noting that the lower sash is for removal, brought somewhat short of the highest position in its own sashway. With the sash and elements in the sashway thus related, and the tongue 100 in socket structure 102, the rollers 37 of the lower sash are approaching the cutaways 43 of the adjacent right hand track element as shown by Fig. 4. The sash may now be given a short lifting movement to bring the portion 90 out of and away from flange 96. Further displacement movement of the sash (now free of the counterbalance), in its own plane, but upwardly and to the right of Fig. 4, enables rollers 37 to enter cutaway portions 43, followed by withdrawal of the left hand side of the sash, then complete removal as heretofore described in reference to sash 10.

After removal of the lower sash, it is reinserted after the manner described with reference to sash 10, namely, by insertion of the right hand sash stile 13 of sash 11 depthwise as far as possible into the right hand sashway. The left hand stile 12 may now be depthwise restored to bring the sash to its normal plane of operation. At this time it should be noted that the coacting abutment elements 90 and 96 are usually laterally displaced. However, with the sash restored to the sashway, a first downward movement thereof causes the camming surface 45 of recess 43 to act on the adjacent rollers 37 to shift the entire sash to the left (Fig. 4) and thus to slide member 90 of the sash carried fixture, into overlying relation to and abutted engagement by the hook-like flange 96 of fixture 95. This action will occur to an extent such that the point 98 will, by the weight of the sash, enter and be seated in

the opening 97 (Fig. 6), and thus restore the lower sash fully to operative position. Continued downward movement of the lower sash will, now obviously, serve to withdraw the tapered tongue 100 from the socket element 102, and act functionally to restore to the sash, the spring loading of the balance unit 50 acting through the cord 51 and fixtures 95 and 65 to complete the connection to the adjacent margin of the sash.

Although the invention has been described by detailed reference to certain preferred forms of structural embodiment, the detail of disclosure should be understood solely in an instructive, and not in any limiting sense, many variants being possible in the several fixtures as well as in the sash assembly and guiding means, all within the intended scope of the claims hereunto appended.

We claim as our invention:

1. A two-part fixture to provide a temporary anchorage for a balance cord in a slideable sash assembly, one of the parts of the fixture including a tongue in the form of a plate element having a shoulder spaced from its free end, the other part being provided with spaced resilient guide plates and resilient tongue-engaging jaws, the said guide plates being adapted to direct the tongue into position between the jaws, one of said jaws having a portion formed to engage and detachably to fit the shoulder of the tongue, one of said fixture parts being secured to the cord and the other being fixed along the sashway, whereby when the tongue and jaws are brought into engagement, the cord is positioned for detachment from, and further connection to the sash.

2. The combination and arrangement of elements as recited by claim 1, but further characterized in that the resilient jaws include a substantially vertical spring jaw formed through a right angle bend below the guide plates, and a resiliently related companion jaw formed through a reversal of said vertical spring jaw, the said companion jaw being provided with an inturned end portion adapted to engage the shoulder of the tongue upon insertion of the tongue into position between the jaws.

3. In a device for arresting a counterbalance cord in removable slideable sash assemblies equipped with a counterbalance and cord, a fixture element adapted for mounting on an edge portion of the slideable sash, and including a horizontal arm projecting from such portion, said arm being in the form of a plate and disposed at an acute angle relative to the plane of the sash, a plate element carried by said cord and having an acutely upturned portion normally disposed substantially parallel to said arm, said plate element and its upturned portion being downwardly convergent with its connecting region normally arranged substantially parallel to said arm to provide a hook adapted for detachable engagement to said arm on the sash fixture element, a vertical tongue on the said plate element, and resilient gripping means arranged for mounting in a sashway, in the path of the slideable sash, said means comprising resilient tongue-engaging jaws and spaced guide plates, said guide plates being adapted to direct the tongue between the jaws, said tongue having a shoulder, one of the jaws having an abutment portion adapted detachably to grip said shoulder of the tongue upon insertion of the tongue into position between the jaws for nullifying the action of the counterbalance cord incident to removal of the sash.

4. A counterbalance retention device for use with a slideable sash and a sashway therefor, consisting of fixtures for rendering captive a counterbalance cord and arresting the function of the counterbalance incident to sash removal, said device consisting of three coacting fixtures, the first fixture consisting of an attachment plate for mounting on an edge portion of a slideable sash, said fixture having a lateral projection, a second fixture secured to the counterbalance cord and comprising a plate element, and a projection connected to and disposed in acute angular relation to the plate element, the plate element and projection of the second fixture being convergent and having its connecting region normally arranged parallel to and receiving the projection of the first said fixture, the second fixture including an end projection in the form of a plate and characterized by a distinct shoulder, and a third fixture adapted to be mounted in fixed position in the sashway in the path of movement of the second said fixture, said third fixture comprising a pair of resilient jaws adapted to receive the end projection of the second fixture therebetween, and a pair of spaced guide portions adapted to receive therebetween the end projection on the second fixture, and to direct said projection between the jaws of said third fixture, one of said jaws having an abutment portion formed to abut and detachably grip the shoulder of the tongue upon insertion of the tongue into position between the jaws.

5. In a counterbalance retainer for removable slideable sash assemblies in which the slideable sash operates in a sashway, and is provided with a counterbalance and cord therefor, a connector device comprised of fixtures a first fixture adapted for attachment to the slideable sash, and including an attachment plate, a projecting arm on said plate; a second fixture attached to the counterbalance cord, and consisting of a plate having its lower marginal region turned upwardly at an acute angle, the plate and its upturned marginal region having its connecting folded region normally arranged parallel to and receiving the projecting arm on the plate of the first said fixture, said fixtures being separable by relative vertical movement of the sash and cord, the plate of the second fixture further including a tapered end projection, and a third fixture to be anchored in the sashway along the path of sash movement, the third fixture including an open-end socket, said socket having resilient jaws and spaced guide plates, the jaws being tapered to conform substantially to the taper of said end projection, the guide plates being adapted to direct the tapered end projection between the tapered jaws, said tapered end projection being engaged by and gripped between the tapered resilient jaws to arrest the counterbalance cord and second fixture, while permitting disconnection of the first said fixture and the sash, from the second said fixture and the balance cord.

6. In a counterbalance retainer for use with removable slideable sash assemblies in which the slideable sash operates in a sashway, and is provided with a counterbalance and cord therefor, a three-part connector device comprised of fixtures a first fixture adapted for attachment to an edge portion of the slideable sash, and including an attachment plate, a projecting arm on said plate; a second fixture attached to the counterbalance cord, and consisting of a plate having its lower marginal region turned up-

wardly at an acute angle, the plate and its upturned marginal region being downwardly convergent to its connecting folded region, the connecting folded region being normally arranged parallel to and receiving the projecting arm on the plate of the first said fixture, the plate of the second fixture further including a tapered end projection, and a third fixture provided with a base portion anchored in the sashway along the path of sash movement, the third fixture further including an open-end socket, said socket having resilient jaws and spaced guide plates, the taper of the jaws conforms substantially to the taper of said end projection, the guide plates being adapted to direct the tapered end projection between the tapered jaws, said tapered end projection being engaged by and gripped between the resilient tapered jaws to arrest the counterbalance cord and second fixture, while permitting disconnection of the first said fixture and the sash, from the second said fixture and the balance cord.

7. A releasable captive device for selectively arresting a counterbalance tape in a slideable sash assembly and providing a detachable connection between the sash and tape, the device including an arm, a base by which the arm is attached to the side of a sash with the arm projected in a direction laterally of the sash, a grooved element having converging sides with its groove normally presented parallel to and receiving the arm, the grooved element being so connected to the tape as to move therewith, said grooved element and arm being separable by relative vertical movement of the sash and tape, a fixture for mounting adjacent the sashway including resilient tongue-engaging jaws and spaced resilient guide plates, and a second fixture movable with the tape, the second fixture including a tongue in the form of a plate element having a shoulder, the guide plates being adapted to direct the tongue between the jaws, one of the said jaws having a portion formed to interfit the shoulder of the tongue under tension of the tape for arresting same when the arm and grooved element are to be separated.

8. A device for selectively arresting a counterbalance tape in a slideable sash assembly and providing a detachable connection between the sash and tape, the device including an arm, a base by which the arm is attached to the side of a sash with the arm projected in a direction laterally of the sash, a grooved element having converging sides with its groove normally presented parallel to and receiving the arm, the converging sides of the grooved element tending to center the arm in parallel relation to the groove of the grooved element, as the arm is inserted downwardly into such groove, the grooved element being so connected to the tape as to move therewith, the grooved element and arm being readily separable by relative vertical movement of the sash and tape, a fixture for mounting adjacent the sashway including resilient tongue-engaging jaws and spaced resilient guide plates, and a second fixture movable with the tape, the second fixture including a tongue in the form of a plate element having a marginal shoulder, the guide plates being adapted to direct the tongue between the jaws, one of said jaws having a portion formed to interfit the shoulder of the tongue under tension of the tape for arresting same when the arm and grooved element are to be separated.

the groove of said grooved element having a bottom notch, and the arm having a portion extending into said notch and tending to keep the arm and grooved member in register.

9. The combination and arrangement of elements as recited by claim 8, but further characterized in that said arm consists of a rigid element having a downwardly presented linear edge portion and further characterized in that said grooved element is formed to present a groove of a substantially V shaped transverse section, the lowermost portion of which is normally abutted by the linear edge portion of said arm, and the converging sides of which tend to center such edge portion in the V shaped groove.

10. In a device for arresting a counterbalance tape, as for removal of sash in a slideable sash and sashway assembly, a fixture for mounting on a side portion of the sash and including a mounting base, a horizontal arm in the form of a plate carried by the base and projecting laterally of the sash, said arm being disposed at an acute angle relative to the plane of the sash, a second fixture to be carried by the tape, and consisting of a plate element, and a projection disposed at an angle relative to the plate element and normally underlying said horizontal arm, a vertical tongue on said second fixture having a shoulder, and a stationary fixture for mounting in the sashway near a limit of travel of the second fixture and including spaced guide plates and resilient tongue-engaging jaws, said guide plates being adapted to direct the tongue between the jaws, one of said jaws having a portion formed to engage and detachably to fit the shoulder of the tongue for retention of the second fixture, and retention therewith of the balance tape incident to sash removal.

11. In a device for arresting a counterbalance tape, as for removal of sash in a slideable sash and sashway assembly, a fixture for mounting on a side portion of the sash and including a mounting base, a horizontal arm in the form of a plate carried by the base and projecting laterally of the sash, said arm being disposed at an acute angle relative to the plane of the sash, a second fixture to be carried by the tape, and consisting of a plate element, and a projection disposed at an acute angle relative to the plate element and normally underlying said horizontal arm, a tapered vertical tongue on said second fixture, the fixture provided with a shoulder in the region of the tongue, and a stationary fixture for mounting in the sashway near a limit of travel of the second fixture and including spaced guide plates and resilient tongue-engaging jaws, said guide plates being adapted to direct the tongue between the jaws, one of said jaws having a portion formed to engage and detachably to fit the shoulder for retention of the second fixture, and retention therewith of the balance tape incident to sash removal.
